UNITED STATES PATENT OFFICE.

AUGUST SUNDH, OF HASTINGS-ON-HUDSON, NEW YORK.

FLEXIBLE TUBING.

Application filed December 20, 1919. Serial No. 346,294.

To all whom it may concern:

Be it known that I, AUGUST SUNDH, a citizen of the United States, residing at Hastings-on-Hudson, in the county of Westchester and State of New York, have invented certain new and useful Improvements in Flexible Tubing, of which the following is a specification.

My invention relates to an improvement in flexible, metallic tubing and it is an object thereof to provide a tube which will be easy to manufacture, one which will withstand high, internal pressures, and one which may be easily repaired.

Briefly, the present invention comprises a flexible, metallic tubing made up of a helically wound, corrugated, metallic strip surrounding a corrugated, metallic tube, the adjacent edges of the metallic strip being brought in proximity to each other at a point above the corrugations of the interior, metallic tube and held in place by a column of solder, which solder at the same time functions as a reinforcement for the tubing.

Referring to the accompanying drawings, wherein embodiments of my invention are illustrated,

Fig. 1 is a part sectional elevation of one form of my metallic tube;

Fig. 2 is an enlarged section of the tubing of Fig. 1.

Referring to the drawings in detail, 1 designates, as a whole, a corrugated, metal strip helically wound to form inwardly and outwardly extending loops 2 and 3, respectively. Enveloped or surrounded by the helically wound, metal strip 1 is an inner, corrugated, metal tube 4, the adjacent edges 5 and 6 of the corrugated, metal strip being brought in proximity to each other at a point above the corrugations 7 of the metal tube 4. From Figs. 1 and 2 it will be seen that the adjacent edges 5 and 6 of the metal strip 1 form in part the inwardly turned loops 2 of the tube, the adjacent edges 5 and 6 of the metal strip, however, being separated from each other a short distance and the space between these edges being filled with a fusible, metallic binder 8, such as solder. This solder functions as a binder to prevent separation of the edges 5 and 6 of the strip 1 and also to bind the strip 1 to the corrugations 7 of the tube 4, the solder also functioning as a reinforcing element for the inwardly turned loops

of the tubing. The solder, as shown in Figs. 1 and 2, passes from the upper surface of the adjacent edges 5 and 6 of the metallic strip 1 between the same at 9 and between the metallic strip and the corrugations 7 of the tube 4, as designated at 10. The solder gradually tapers outwardly from the bottom of the inwardly turned loops so as to cause the flexibility of the loops to progressively increase outwardly in order that there will be no danger of fracture of the tubing at the edge of the binder.

It will be seen, therefore, that I have provided a flexible, metallic tubing where- 70 in the outwardly turned loops 3 thereof are free to impart the desired flexibility to the tubing as a whole, and one wherein the inwardly turned loops 2 are more or less rigid 75 at the bottom thereof by reason of the fusible, metallic binder 8 and the corrugated, metal tube 4, so that as a whole the tubing, while possessing the desired flexibility, will at the same time successfully withstand 80 high, internal pressures.

It will be seen also that the fusible binder 8 employed in this construction tapers gradually to each side thereof so that the flexing of the inwardly turned loops or corrugations of the tubing will progressively increase from the bottom of the inwardly turned loops instead of taking place merely at the junction of the binder and the walls 85 of the loops.

It will be obvious also that in the event 90 of rupture of the tubing at the inwardly turned loops, the same is accessible and may be easily repaired.

What I claim as new is:

A flexible tubing comprising a corrugated, 95 metal tube, a helically wound, corrugated, metal strip surrounding the same and forming inwardly and outwardly extending loops, adjacent edges of the strip approaching each other at a point above the corrugations of said tube, and a fusible, metallic binder for preventing retraction of the edges of the strip and for binding said edges of the metal tube, said fusible binder tapering outwardly from the base of the said 100 inwardly turned loops to impart a gradually increasing flexibility to the walls thereof.

This specification signed this 15 day of December, 1919.

AUGUST SUNDH.
